UNITED STATES PATENT OFFICE

PAUL HALBIG, FELIX KAUFER, AND PETER SCHMITZ, OF MUNICH, GERMANY, AS
SIGNORS TO DR. ALEXANDER WACKER GESELLSCHAFT FÜR ELEKTROCHEMISCHE
INDUSTRIE G. M. B. H., OF MUNICH, BAVARIA, GERMANY

METHOD OF PRODUCING KETO ACID ESTERS

No Drawing. Application filed August 1, 1928, Serial No. 296,861; and in Czechoslovakia April 26, 1928.

It is usually assumed that the alkyl esters of the same acid show in general similar chemical characteristics. Thus in condensations in which an alkyl radical splits off, it should be immaterial whether the acid is esterified with a methyl-, ethyl-, butyl-, or amyl- alcohol group. Therefore nearly all ester condensations have been effected by means of the ethyl- or methyl- esters, since 10 the corresponding alcohols can be obtained easily and cheaply.

In ester condensations by means of metallic sodium the effect of a change in the alkyl radical (or alcohol) is small. The action of metallic sodium on butyl acetate causes, e. g. a yield of 36% while that of sodium on ethylacetate according to the known reactions causes a yield of 39% of the theoretical. These ratios are unexpectedly 20 changed when the esters are condensed by means of metal alcoholates, particularly alkali metal alcoholates, such as sodium alcoholate.

For example, according to this invention, 25 the action of sodiumbutylate on butylacetate yields surprisingly about 80% or more based on the sodium, used in the form of sodium butylate. The invention therefore comprises the production of keto acid esters of butyl 30 or higher alcohols by treatment of the carboxylic acid esters with a metal alcoholate, preferably of the alkali metal group.

The substitution of metallic sodium by the metal alcoholate not only effects an essential 35 improvement in yield in the case of butylacetate, but a number of further advantages are obtained. First, the fire hazard of working with metallic sodium is avoided. Furthermore, the metal alcoholates can be produced cheaper than the metallic sodium, and 40 finally the working up of the higher esters of the keto acid can be accomplished easier and with smaller losses because of their lower water solubility, than that of the esters of the lower alcohols. For the further working 45 of the keto acid esters, which mainly serve for condensations in which the alkyl radical is split off, the introduction of the alkyl radicals higher than ethyl has the further ad-

vantage that the higher alcohols can be recovered in anhydrous form with little trouble.

Example 1

96 parts of sodium butylate are heated with 55 350 parts of butylacetate and the resulting butyl alcohol in mixture with butyl acetate is distilled off by means of a column; fresh butylacetate is added as required. The residue is acidified e. g. with acetic acid. The 60 salt is removed and the ester mixture is fractionated preferably in vacuum. The yield of acetoacetic acid butyl ester passing over at 16 m/m between 100° and 103° amounts to 65 90% or more, calculated on the basis of the sodiumbutylate employed.

Example 2

110 parts of sodiumamylate are heated with 70 650 parts amylacetate and are treated as in Example 1. The yield of acetoacetic acid amyl ester boiling point 105-108° at 16 m/m amounts to over 80% on the basis of the sodiumamylate employed.

In the same manner butyl- or amylacetate 75 can be condensed with other mono-carboxylic acid esters with the help of alcoholates. The esters of di- and poly-carboxylic acids can likewise be subjected to this condensation. In this manner oxalacetic acid butyl ester 80 can be smoothly produced.

Claims:

1. Method of producing keto acid esters comprising reacting a carboxylic acid ester of an aliphatic alcohol having more than three carbon atoms with an alkali metal alcoholate of an aliphatic alcohol having more than three carbon atoms. 85
2. Method of producing keto acid esters comprising reacting a carboxylic acid ester of an aliphatic alcohol having more than three carbon atoms, with the corresponding alkali metal alcoholate. 90
3. Method of producing keto acid esters comprising reacting a mono-carboxylic acid ester of an aliphatic alcohol having more than three carbon atoms with the corresponding alkali metal alcoholate. 95
4. Method of producing acetoacetic acid esters comprising reacting an acetic acid ester 100

of an aliphatic alcohol having more than three carbon atoms with an alkali metal alcoholate of an aliphatic alcohol having more than three carbon atoms.

- 5 5. Method of producing acetoacetic acid butyl ester comprising reacting butyl acetate with sodium butylate.
- 10 6. Method of producing acetoacetic acid amyl ester comprising reacting amyl acetate with sodium amylate.

10 Signed at Munich, this 23rd day of June,
A. D. 1928.

DR. PAUL HALBIG.
DR. FELIX KAUFLER.
